UNITED STATES PATENT OFFICE.

WALFRID WALLENTHIN, OF ATTLEBORO, MASSACHUSETTS, ASSIGNOR TO W. W. ASSOCIATED ATTLEBORO MANUFACTURERS, INC., OF ATTLEBORO, MASSACHUSETTS, A CORPORATION OF MASSACHUSETTS.

UNDERSWUNG CAM BUCKLE.

Application filed April 17, 1923. Serial No. 632,788.

To all whom it may concern:

Be it known that I, WALFRID WALLENTHIN, a citizen of the United States, residing at Attleboro, in the county of Bristol and State of Massachusetts, have invented certain new and useful Improvements in Underslung Cam Buckles, of which the following is a specification.

My invention relates to buckles of the type wherein a pivoted cam provides the band gripping means.

An object of my invention is to provide a buckle equipped with an underslung pivoted cam gripping member for more effectually gripping and binding the inserted band. I am aware that it is old in the art to provide buckles of the general pivoted cam type. In my invention, however, a cam is pivoted in such a manner that as it is swung into 20 gripping position it is pulled under rather than over its pivot points.

A further object of my invention is to provide in a buckle of the type described a swinging cam lever of the second class. Cams of this general type may be considered as levers. Hitherto the work arm or gripping portion of the cam lever has been situated on the opposite side of the fulcrum or pivot points thereof from the power arm or band attaching extension, thus providing a lever of the first class. In my invention, however, the gripping portion or work arm of the cam lever is situated between the fulcrum or pivot points thereof and the band attaching extension or power arm thereof. As the gripping portion is preferably of a general convex shape, it is therefore possible to mount it in much closer functional relation to the band, thereby permitting the use 40 of a minimum amount of metal. It is obvious that due both to the underslung feature mentioned above, and to the fact that a lever of the second class is employed, that a lesser amount of material is required 45 to make a workable lever, that it may be more easily released, that it is at all times near the band, and that it is more sure in its binding action. From its inherent structure the gripping portion is able to function 50 through a much wider arc, than has heretofore been possible with overslung types of cams, cam levers of other classes, and other types of cams or gripping means employed, thus permitting its use on arm bands, garters,

etc., where the object to be gripped is of 55 comparatively small diameter, and where the cam must function at a greater angle to the tangent at the gripping point than for belts. Overslung cams and cam levers of the first class especially where forced to 60 function at a comparatively large angle to the tangent at the gripping point, will tend to lose their grip. It is obvious that the operation of setting the buckle is greatly facilitated, for it is only necessary to partially 65 close the cam by hand, and the stretching of the band will cause the cam to pivot further and more effectually bite in and grip the band. As the gripping portion is forced down against the band, it will more readily 70 and successfully function than where it is forced up and around against it as in former types. Further stretching of the band only makes the buckle function better.

A further object of my invention is to provide a buckle having a convex gripping surface of slight curvature. It is due to this feature that many of the advantages mentioned in the preceding paragraph are possible.

A further object of my invention is to provide a buckle wherein the cam will automatically adjust itself to accommodate varying thicknesses of belts.

A further object of my invention is to provide a swinging cam with a transverse slot into which portions of the rough surface of the band are forced, and with teeth if desired to thereby more effectually grip and bind the band.

A further object of my invention is to provide a buckle having a cam which will be stamped out in its entirety of a single piece of metal, thereby obviating the necessity for and complications of having separate pieces for the pin, gripping member, bail or loop, plate etc. of former types.

These and such other objects of my invention as may hereinafter appear will be best understood from a description of one embodiment thereof, such as is shown in the accompanying drawings applied to a belt buckle.

In the drawings, Fig. 1 is a front elevation of the buckle in operative position.

Fig. 2 is a longitudinal section taken along the line 2—2 of Fig. 1.

Fig. 3 is a longitudinal section similar to

Fig. 2 illustrating how the buckle still functions when the cam is only partially closed.

Fig. 4 is a longitudinal section similar to Fig. 2, showing the cam in open position.

5 Fig. 5 is a cross section taken along the line 5—5 of Fig. 2.

Fig. 6 is a plan view of the pivoted cam member.

10 Fig. 7 is an end view of the pivoted cam member.

In the drawings, wherein like characters of reference indicate like parts throughout, 1 designates generally the binding member, provided with the pivot flanges 2 at each 15 side thereof, said flanges being provided with holes 3, for mounting the pivoted or swinging cam member 4 therein. For the purposes of my invention the member 1 may merely comprise a simple cross bar 20 with pivot flanges at each side thereof. I have illustrated it in the drawings, however, as comprising the front plate or casing 1, common in belt buckles of the type shown, provided with the side flanges 2 which serve 25 as pivot flanges, and also to keep the free end 5 of the band 6 in place, and the turned over lips 7 to further encase said free end 5.

It is obvious that due to the convex shape of the gripping surface 15 of the cam, that 30 the cam will swing into gripping position as heretofore explained. When different thicknesses of belts are used, it is evident that the cam will adjust itself to a firm gripping position intermediate the positions 35 shown in Figures 2 and 3, said position depending upon the thickness of the belt used. This feature is not possible where semi-circular cams of small diameter are used, as in former types.

40 It is clear that I have provided a buckle of simple construction, composed of two members only, each of which may be conveniently stamped out of a single piece of metal, which members perform in a better 45 and more efficient manner all of the functions of the many members of former types, as well as the new functions heretofore explained.

The cam member 4 is preferably stamped 50 out of one piece of metal, so as to make all portions thereof integral with the others. The cam member 4 is provided with a gripping portion having an extended gripping surface of convex shape 15 for gripping the free end of the belt against the binding member. And in my preferred embodiment the entire gripping portion 14 is shown of a general concavo-convex structure, (Fig. 5). Thus in my preferred embodiment the 55 gripping portion is integrally attached to the side flange 16 which projects rearwardly therefrom.

On each side of the cam member are placed the pivotal projections or pintles 10, which thus extend laterally from said side

flanges 16 of my preferred embodiment near the inner end of said cam member 14. It is thus obvious that the gripping portion 14 extends integrally outwardly from said pivotal lugs and that said gripping surface 15 is integrally offset from said lugs on pintles 10 so that the gripping surface 15 may freely pivot away from the surface of the band. At the opposite outer end 21 of said cam member 4 is situated the band attaching extension means, which preferably comprises the bail 11 integral therewith, and which thus extends integrally outwardly therefrom at the outer end thereof. It is thus obvious that the cam member 4 is one integral unit, comprising in my preferred embodiment a member having the pivotal lugs 10 extending laterally therefrom near the inner end thereof, side flanges 16 projecting forwardly from said lugs 10, a gripping portion 14 having an extended surface 15 of convex shape of slight curvature for gripping the free end 20 of a belt 6 against the binding member 1 integrally attached to said side flanges 16 and extending outwardly from said pivotal lugs 10 and a bail 11 extending integrally outwardly therefrom for permanent attachment thereto of the belt end 12. As the pintles 10 are mounted on the side flanges 16 of the cam member 4, it is obvious that the gripping portion 15 will be integrally offset from said lugs 10. One end 12 of the band 6 is conveniently fastened around said bail 11, leaving the other end 5 free as stated. Between said pintles or pivotal lugs 10 and the bail or band attaching extension or power arm 11 is placed the work arm or band gripping portion 14 of said cam 4, thus providing a cam lever of the second class. The gripping surface 15 of said portion 14 is preferably of a general convex structure as shown in Fig. 7 and may be provided if desired with a transverse slot 17 and teeth 18 for more effectually biting in and gripping the surface of the band 6. The pivotal lugs 10 of the cam member 4 are inserted in the pivot holes 3 in the pivot flanges 2 situated at each side of the binding member 1, and the end 12 of the band 6 permanently fastened as at 19 to the bail 11. As stated, the pivot holes 3 are preferably so situated on the pivot flanges 2 of the binding member 1, as to allow such a distance between the binding member 1 and said pivot holes 3, that as the cam member 4 is swung into operative position, the gripping portion 14 thereof biting against the surface of the inserted free end 5 of the band 6, it will swing entirely underneath said pivot holes 3. I employ the word "band" to include any member, preferably flexible, employed to encircle or bind any desired object to any other, such as a belt band, arm band, leg band, or garter, etc.

For a reason to be explained, my invention is peculiarly adapted for use with a band binding an object of comparatively small diameter such as an arm or leg.

5 In operation, the cam member 4 is swung around to the open position shown in Fig. 4, to allow the free end 5 of the band 6 to be conveniently inserted between said cam 4 and binding member 1. The free end 5 of 10 the band 6 is pulled through, and the band tightened the desired amount.

The cam 4 is either manually closed the entire distance as shown in Fig. 2 or swung to the approximate position shown in Fig. 3. 15 When in the position shown in Fig. 3, the gripping portion 14 of the cam 4 will start to function against the inserted free end 5 of the band 6, and the stretching of the band 6 will cause the cam 4 to automatically swing 20 to the position shown in Fig. 2, due to the fact that it is underswung and a cam lever of the second class is employed as explained. To unbuckle, it is merely necessary to manually swing the cam to the position shown 25 in Fig. 4, where the free end 5 of the band 6 may be readily loosened or pulled out.

Figs. 2 and 5 illustrate how rough portions 20 of the surface of the free end 5 of the band 6 sink into the transverse slot 17, thus 30 more tightly and effectually holding the band 6 in position.

Fig. 3 illustrates the reason why my invention is peculiarly adapted to bind an object of comparatively small diameter such 35 as an arm or leg, and shows how due to the inherent underswung construction of the cam 4, and to the fact that a cam lever of a second class is employed, the gripping portion 14 thereof is able to function through a 40 wide arc, and even function at a comparatively great angle to the tangent at the gripping point. One may visualize Fig. 3 as comprising a simple cross bar binding member 1 with the cam member 4 suitably pivot- 45 ed to the flanges 2 situated at each end thereof, employed on an object of small diameter such as an arm, and thus see how well my invention will function under such conditions.

50 I employ the terms "forwardly" and "rearwardly" relative to the radial position of the buckle on the wearer's body and the terms "inner" and "outer" relative to the centre line of the buckle.

55 It is understood that my invention is not limited to the specific embodiments shown and that various deviations may be made therefrom without departing from the spirit and scope of the appended claims.

60 What I claim as new and desire to secure as Letters Patent is:

1. In a buckle, the combination of a binding member provided with pivot flanges on each side thereof and a cam member having 65 pivotal lugs extending laterally therefrom

near the inner end thereof, side flanges projecting forwardly from said lugs, a gripping portion having an extended surface of convex shape of slight curvature for gripping the free end of a belt against said binding member integrally attached to said side flanges and extending outwardly from said pivotal lugs and a bail extending integrally outwardly therefrom for permanent attachment thereto of a belt end, said cam member being pivoted on the flanges of the binding member. 70

2. In a buckle, the combination of a binding member provided with pivot flanges on each side thereof and a cam member having 80 pivotal lugs extending laterally therefrom near the inner end thereof, side flanges projecting forwardly from said lugs, a gripping portion having an extended surface of convex shape for gripping the free end of a belt against said binding member integrally attached to said side flanges and extending outwardly from said pivotal lugs and a bail extending integrally outwardly therefrom for permanent attachment thereto of a belt 85 end, said cam member being pivoted on the flanges of the binding member. 90

3. In a buckle, the combination of a binding member provided with pivot flanges on each side thereof and a cam member having 95 pivotal lugs extending laterally therefrom near the inner end thereof, side flanges projecting forwardly from said lugs, a gripping portion having an extended surface convex on every line of section for gripping 100 the free end of a belt against said binding member integrally attached to said side flanges and extending outwardly from said pivotal lugs and a bail extending integrally outwardly therefrom for permanent attachment thereto of a belt end, said cam member being pivoted on the flanges of the binding member. 105

4. In a buckle, the combination of a binding member provided with pivot flanges on 110 each side thereof and a cam member having pivotal lugs extending laterally therefrom near the inner end thereof, side flanges projecting forwardly from said lugs, a gripping portion having an extended surface of convex shape of slight curvature provided with transverse slots for gripping the free end of a belt against said binding member integrally attached to said side flanges and extending outwardly from said pivotal lugs 115 and a bail extending integrally outwardly therefrom for permanent attachment thereto of a belt end, said cam member being pivoted on the flanges of the binding member. 120

5. In a buckle, the combination of a binding member provided with pivot flanges on each side thereof and a cam member having 125 pivotal lugs extending laterally therefrom near the inner end thereof, side flanges projecting forwardly from said lugs, a gripping

portion having an extended surface of convex shape of slight curvature provided with transverse slots and teeth for gripping the free end of a belt against said binding member integrally attached to said side flanges and extending outwardly from said pivotal lugs and a bail extending integrally outwardly therefrom for permanent attachment thereto of a belt end, said cam member being pivoted on the flanges of the binding member.

6. In a buckle, the combination of a binding member provided with pivot flanges on each side thereof and a cam member having

pivotal lugs extending laterally therefrom near the inner end thereof, side flanges projecting forwardly from said lugs, a gripping portion having a surface for gripping the free end of a belt against said binding member integrally attached to said side flanges and extending outwardly from said pivotal lugs and a bail extending integrally outwardly therefrom for permanent attachment thereto of a belt end, said cam member being pivoted on the flanges of the binding member.

In testimony whereof I affix my signature.

WALFRID WALLENTHIN.
